UNITED STATES PATENT OFFICE.

JAMES L. BREESE, JR., OF CHICAGO, ILLINOIS, ASSIGNOR TO QUAKER MANUFACTURING COMPANY, OF CHICAGO, ILLINOIS, A CORPORATION OF ILLINOIS.

SMALL OIL-BURNER-STOVE UNIT.

Application filed February 8, 1926. Serial No. 86,697.

My invention relates to an oil heater and particularly to a small oil heating unit for domestic use. One object is the provision of a small oil burner heating unit. Another object is the provision of such a unit in which the supply of air and the supply of fuel to the combustion zone are simply and easily controlled. Other objects will appear from time to time in the course of the specification.

I illustrate my invention more or less diagrammatically in the accompanying drawings, wherein—

Figure 1 is a vertical section;

Figure 2 is an enlarged detail section; and

Figure 3 is a detail section of the control valve.

Like parts are indicated by like symbols throughout the specification.

A generally indicates a stove assembly having the legs A¹ and the bottom member A² with the downwardly depending rim A³.

B is an outer cylindrical section resting upon the bottom A² and supporting the partition ring B¹ having an upwardly projecting flange B² and the downwardly depending flanges B³ B⁴. The flange B³ serves to center the ring B¹ within the cylinder B and the flange B⁴ centers the inner burner drum or cylinder B⁵. The drum B⁵ is perforated at a plurality of points as at B⁶ and is provided with an upper line of larger or more frequent perforations B⁷. Its bottom is closed by a concave plate B⁸ in which is preferably a bed of sand or similar finely divided material B⁹. Communicating with it is the oil line B¹⁰.

C is the upper stove cylinder, or radiating member, resting upon the plate B¹ and centered by the flange B². It is closed, for example by the lid C¹, which is provided with an opening C² and a cover C³, therefor.

C⁴ is a flue for the exhaust gases of combustion. C⁵ is a gate member closed by the swinging gate C⁶. C⁷ C⁸ are outwardly projecting downwardly depending rings for protective and ornamental purposes.

D is any suitable fuel tank, with the removable lid D¹. It is supported for example by an upper leg D² and a lower leg D³ the two being slotted in opposition as at D⁴ to

permit the passage of an adjusting screw D⁵. D⁶ is a float chamber, separated from the interior of the tank by the horizontal partition D⁷. D⁸ is a strainer adapted to surround the inlets D⁹ to the oil passage D¹⁰. The passage D¹⁰ is controlled for example by the shut-off valve stem D¹¹ which is screw threaded as at D¹² for axial movement in response to rotation.

E is a float in the form of a shallow pan with an interior generally cylindrical portion E¹ and a float valve point E².

The fuel line B¹⁰, which extends from the float chamber D⁶ to the concave burner plate B⁸, is controlled for example by the valve G in which is positioned a valve seat G¹ and a needle G² controlled by the valve stem G³. The stem G³ is pivoted to a lever G⁴ which in turn is pivoted intermediate its ends upon the bracket G⁵. A link G⁶ depends from its opposite end and is pivoted to one arm of the bell crank lever G⁷, the opposite arm of such lever being secured to the rod G⁸ which extends to the air controlling slide G⁹ adapted to control the air inlet G¹⁰. G¹¹ is a control rod engaging the opposite end of the slide G⁹ and terminating in an external handle member G¹².

It will be realized that whereas I have illustrated a practical and operative device that nevertheless many changes might be made in the size, shape, number and disposition of parts without departing from the spirit of my invention and that I wish my description to be taken as in a broad sense diagrammatic and illustrative rather than as limiting me to my specific showing.

The characteristic method or process of combustion effected with the present burner is described in greater detail and claimed in co-pending applications.

The use and operation of my invention are as follows:

I illustrate a stove unit comprising a lower drum and an upper drum, the combustion drum proper being centered within the lower drum, its open top communicating with the bottom of the upper drum, the lower drum being indicated as B, the upper drum as C and the inner burner drum or cylinder as B⁵. In the use of my device the upper drum is the flame container and

the radiating member proper. The lower drum B houses and protects the combustion drum B⁵ and provides it with a controlled supply of air, the combustion drum being 5 perforated throughout its periphery. The supply of air is controlled by the slide or damper G⁹ in the air inlet G¹⁰, such inlet being the sole passageway through which air is permitted to flow inwardly into the 10 combustion unit.

The combustion drum B⁵ is herein shown as provided with a concave bottom in which is positioned a layer of sand or similar finely divided material. Any suitable means may 15 be employed to deliver a supply of oil to this concave bottom, and I illustrate an oil tank D with a float chamber D⁵. This float chamber serves to control the level of oil in the concave bottom of the cylinder B⁵, the details of float chamber and float being 20 above described but forming no part of the present invention. It is sufficient to point out that when the oil in the float chamber D⁵ is depleted, the drop in the float permits an 25 increased supply of fuel to flow into the float chamber. This inflow of fuel, in turn, flows along the line B¹⁰.

I provide means for controlling the volume of flow along the line B¹⁰, namely the 30 valve G actuated by the valve stem G³ which may be moved in unison with the slide or chamber G⁹, in response to movement of the handle G¹². I thus provide an automatic increase of the fuel flow in response to an 35 increase of the inflowing volume of air, although, if desired, this automatic flow may be dispensed with.

It is characteristic of my burner that the 40 liquid fuel is vaporized by the radiant heat of the combustion going on above it and that an incombustible or only partially combustible mixture is formed in the bottom and throughout the body of the cylinder B⁵, which does not become fully combustible 45 until it receives the additional mixture of air through the upper line of ports B⁷, the vaporized fuel rising steadily, during this mixing process, until it reaches the area of complete combustion.

50 As earlier shown, the wall of the cylinder B⁵ is penetrated along its upper portion by a row of relatively large or relatively numerous apertures, which direct a series of converging jets of air. The lower portion 55 of the walls of the cylinder B⁵ is penetrated by a number of small apertures, and I prefer a large number of small apertures to a small number of large apertures, since I thus avoid eddy currents and cut down the length 60 of directed flow of the pencils of inflowing air.

The liquid fuel in and along the surface of the sand bed is vaporized by the radiant heat of combustion and must therefore rise 65 upwardly from the sand. The inflowing air

through the apertures B⁶ is insufficient to support complete combustion but forms a rich mixture.

As the rich mixture reaches the level of the upper row of apertures it is thinned out and mixed with air sufficient to support complete combustion.

70 It is essential that any back-draft be avoided, since delicate balance of combustion is immediately overthrown. I therefore employ the flap gate C⁶ which is lightly hinged in the aperture C⁵. In case there is a back-draft down the flue C⁴, instead of causing an eddy of cold air into the drum B⁵ it merely thrusts out the gate C⁶, which thus relieves the pressure in the cylinder C, and permits the regular upward movement of the vaporized fuel from the cylinder B⁵ into the cylinder C and its consequent normal combustion. The normal draft being up the flue 80 C⁴, the consequent reduced air pressure within the cylinder is sufficient to hold the door C⁶ normally in position.

I claim:

1. In an oil heater, a radiating member, a mixing and combustion chamber associated therewith and in communication with the interior thereof, means for delivering air to said combustion chamber, a flue passage extending from the radiating member, and a member, associated with said radiating member, adapted to indicate back-drafts down said flue, and into said radiating member and combustion chamber.

2. In an oil heater, a radiating member, a mixing and combustion chamber associated therewith and in communication with the interior thereof, means for delivering air to said combustion chamber, a flue passage extending from the radiating member, and a member, associated with said radiating member, adapted to indicate back-drafts down said flue, and into said radiating member and combustion chamber, comprising a hinged gate of light material mounted in the wall of said radiating member.

3. In an oil heater having a radiating member and a combustion chamber associated therewith, combined observation and back-draft indicating means comprising a hinged gate of translucent material, said gate being mounted in the wall of said radiating member.

4. In an oil heater, a radiating member, a mixing and combustion chamber associated therewith and means for supplying liquid fuel and air thereto, an exhaust member for the outlet of the gases of combustion and means for indicating a back-draft down such member and into the combustion chamber.

5. In an oil heater, a radiating member, a mixing and combustion chamber associated therewith and means for supplying liquid fuel and air thereto, an exhaust member for the outlet of the gases of combustion and

means for indicating a back-draft down such member and into the combustion chamber comprising a hinged flap and an inner abutment therefor.

- 5 6. An oil heater comprising a radiating member, a flue extending therefrom, a combustion chamber positioned at the bottom of the radiating member and upwardly communicating therewith, the wall of the combustion chamber being provided with a plurality of apertures, an air chamber surrounding said combustion chamber and in communication with said radiating member only through said apertures, an air inlet 10 for said air chamber and means for controlling it, a fuel line extending to said combustion chamber, means for controlling the flow of fuel therealong, and a member, associated with said radiating member, 15 adapted to indicate back drafts down the flue and to permit the escape of air from said radiating member during such back-drafts.
7. An oil heater comprising a base member, a drum mounted thereupon, a bottom member for said drum, penetrated by an air admission aperture, an adjustable closure 20 in said aperture, an annular partition member supported within the upper edge of said

drum, an inner perforated drum in engagement therewith and downwardly depending therefrom within said first mentioned drum, a radiator member positioned above said first mentioned drum and supported upon said annular partition member, a cover member 30 therefor and a flue in connection therewith.

8. An oil heater comprising a base member, a drum mounted thereupon, a bottom member for said drum, penetrated by an air aperture, an annular partition member supported upon the upper edge of said drum, a downwardly depending centering flange about the outer edge thereof, a downwardly depending flange about the inner edge thereof, an inner perforated drum in engagement 40 with and centered by said inner flange, and downwardly depending within the outer drum, a fuel line extending to said inner drum, a radiator member projecting upwardly from and supported upon said annular partition member, a centering flange therefor, upwardly projecting from said member, a cover member and a flue for said radiator.

Signed at Chicago, county of Cook and 45 State of Illinois, this fifth day of February, 1926.

JAMES L. BREESE, JR.
